GAS HEATER

Filed July 28, 1920

Fig. 4.

Fig. 5.

August J. Hartfield:
By his attorney

UNITED STATES PATENT OFFICE.

AUGUST J. HARTFIELD, OF LOS ANGELES, CALIFORNIA.

GAS HEATER.

Application filed July 28, 1920. Serial No. 399,537.

To all whom it may concern:

Be it known that I, AUGUST J. HARTFIELD, a citizen of the United States, residing in Los Angeles, county of Los Angeles, State 5 of California, have invented new and useful Improvements in Gas Heaters, of which the following is a specification.

This invention relates to that class of heaters generally known as gas heaters and generally used for domestic and similar heating 10 purposes; and it is an object of the present invention to provide a simple inexpensive heater which will radiate a maximum amount of heat from the gas fuel. It is an 15 object of the present invention to provide a simple heater which may be quickly and easily manufactured and assembled, and it is an object to provide in a heater of the general type here described, a means for facilitating quick and easy starting of the circulation 20 of air and heated products of combustion, so that the heater may quickly be gotten into full operation.

The invention will be best understood 25 from the following description and accompanying drawings in which—

Fig. 1 is a vertical, central, longitudinal section of a preferred form of heater provided by the present invention; Fig. 2 is a 30 horizontal section taken as indicated by line 2—2 of Fig. 1; Fig. 3 is an enlarged detail sectional view taken as indicated by line 3—3 on Fig. 1; Fig. 4 is an enlarged longitudinal detail sectional view taken as indicated by line 4—4 on Fig. 1; Fig. 5 is a vertical horizontal sectional view taken as indicated by line 5—5 on Fig. 2 and Fig. 6 is a 35 partial sectional view showing the heater door in its open position.

Throughout the drawings the numeral 10 designates a central combustion chamber in which the burner is located, and on each side of this central combustion chamber is a plurality of radiating tubes or elements 11 40 through which heated gases pass and from which the heat is radiated. These radiating elements 11 may be made of any suitable material and made in any suitable configuration. It may be here stated that any number 45 of elements 11 may be used and that the method of assembling here shown is merely typical and that the invention is not in any way limited to the number of elements or manner of construction.

It is preferred that the elements 11 be

made of sheet metal and be held together by forming flanges, which are crimped over a part of the next adjacent element 11. These elements are provided with suitable communicating openings 12 formed in their upper 60 and lower portions. The outer radiating elements 11 have openings on one side only. The radiator elements 11 are formed with vertical passages 13 through which the heated gases circulate. These elements are all 65 held together and secured to the central combustion chamber 10.

The central combustion chamber 10 is provided with side walls 14, preferably of sheet metal, and with front and back walls 15 of 70 similar material in a single piece which passes upward, then over the top and then downwardly. The walls 15 are secured to side walls 14 by crimping. The side walls 14 have openings similar to the opening 12 of 75 the radiator element 11, and in this manner provide communication with the radiator elements 11.

Within the central combustion chamber 10 is arranged a burner 16 which is supplied 80 with gas fuel through pipe 17 which is arranged longitudinally in the lower portion of the heater. It is preferred that the pipe 17 be so arranged that it will pass through the lower openings 12 formed in all the radiatorelements and the central combustion chamber, as will be clearly seen in Fig. 1 in the drawings. In front of the burner, that is in 85 the front wall 15, there may be a door 18 which may be opened for igniting the gas in 90 the burner.

The burner 16 is preferably made of cast iron, or the like, and is provided with a vertical opening 19, which is arranged to receive a suitable cup 20 in which the gas is 95 delivered for burning. The cup 20 is preferably made of cast iron, and is so arranged as to fit loosely within the opening 19 formed in the burner 16. The cup 20 may be provided with projections 20^a which assist in holding the cup 20 in the desired position. The cup 20 is supported within the opening 19 by pipe 17, which is in two sections, one section entering the cup 20 on one side and the other section entering the opposite side. The ends of the sections of the pipe 17 are left open and are screw-threadedly engaged to cup 20 so the gas may escape into the cup. The opening 19 is arranged vertically in the burner casting 21, 110

and extends through the entire casting of the burner 16. This feature provides a free vertical passage for the air, from the bottom upward and around the cup 20, and then into the central combustion chamber 10. The burner casting 21 is preferably provided at its sides with outward extending portions 22, which enclose passageways 28 and are arranged to fit within the lower opening 12 formed in the central combustion chamber 10, and the radiator elements 11. To the rear, is an extension 21^a of the casting enclosing a discharge outlet 21 communicating with discharge flue 21^b. The exhaust gases reach outlet 21 by passing through passages 30 from passage 28. It is preferred that the wall 15 be provided with a suitable opening 15^a to allow the exhaust extension 21^a to pass through and extend outwardly a sufficient distance to allow the flue pipe or the like 21^b to be slipped over the extension. The burner casting 16 is supported in place in the structure by its extensions 22 extending through openings 12, by extension 21^a extending through opening 15^a, and also by a supporting lug 16^a which may be screw or bolt connected to the front wall 15.

A suitable funnel shaped hood 23 is arranged within the central combustion chamber, somewhat above the burner 16, and is secured to the side walls 14 and also to the front and back wall 15 of the central combustion chamber. It will be readily seen that the products of combustion which arise from the burner 16 will pass upwardly in a somewhat large volume and upon striking the hood 23 will be more or less concentrated and will then be injected upwardly into the upper part of the combustion chamber. From here they pass in either direction through the openings 12 into the radiator elements. After the gases have entered the radiator elements 11 they become somewhat chilled and pass downwardly to the lower openings 12. They here pass toward the center of the heater. The gases here pass through outlet 21 and into the stack.

In the normal operation of the heater, after having been once started, the gases burn upwardly from the cup 20 and burner casting 16, up through hood 23 and into the upper part of the combustion chamber 10. Air for this combustion comes from the mixer at 17^a on pipe 17 (the mixer and gas feed at 17^b may be put on either section of pipe 17) and comes also upwardly through the passage 19 which takes air through air inlet 25. Under normal operating conditions air for finishing combustion may be drawn in above hood 23 at the openings 24; but whether air is drawn in here or gases slightly pushed out here and the amount of such in flow or out flow, depend

upon operating conditions. These openings serve generally as equalizer openings between the exterior atmosphere and chamber 10; but in ordinary full operation it is preferred that a small amount of air be constantly drawn in.

When the heater is being warmed up on starting the hood 23 plays an important part in directing the upwardly rising heated gases of combustion into the central part of the combustion chamber. The chamber 10 is at that time filled with cold air; and if the gases of combustion rising from below has to bodily push that cold air up through the chamber 10 and also push the whole column of air down around the radiator elements (through a sort of inverted trap), the action is very slow. But when the hot gases are injected into the center of the body of air in chamber 10, that body of air is largely displaced through openings 24 and the hot gas flow freely upwardly to the top of the radiator. Having once reached the top and spread out and begun to cool they then drop down through the radiator elements. Thus the heater is easily and quickly started; there is none of that sluggish starting action so common to ordinary heaters. The cold air above hood 23 does not pass below that hood and the large volume of air in the chamber is thus prevented from moving down on and interfering with the flame at the burner below.

The openings at 26 below the hood 23 also perform the function of allowing escape of cold air on starting; but their normal purpose is to admit air for completion of combustion in that part of the flame directly over the burner.

It may be here stated that this gas radiator may be made of cast iron in one or more units, or it may be made of sheet metal and secured together in any suitable form, and is not in any way limited to the usage shown in the drawings and described in the specification, but is merely shown as a typical illustration of a possible method of manufacture, and one which proved to be of great commercial value. Inasmuch as the parts used in this radiator are practically all made of sheet metal and may be stamped in the necessary configuration and cut in any convenient size, and then crimped in one operation and held securely together, my design provides a simple and easily constructed heater. The heater provided by the present invention is not only simple in regard to manufacture, but is extremely simple in operation, in that there are no dampers or automatic control valves, or the like.

The door shown at 18 is a simple and convenient kind for this purpose. It has hooks 18^a at its lower edge which hook over and behind a roll 15^b on front wall 15, in such a manner that the door may be thrown out

to the position shown in Fig. 6; or it may be readily lifted clear out of the door opening if desired.

Having described a specific form of embodiment of the present invention I do not wish to limit myself to the details contained herewith, but wish to reserve to myself any modifications, variations or changes that may appear to those skilled in the art or fall within the scope of the following claims.

Having described a preferred form of my invention, I claim:

1. A heater of the character described embodying an upright combustion chamber and a side radiator element communicating therewith at its top; characterized by a combined burner and passage member located at said lower end communication and embodying a body having therein a burner chamber, a vertical air passage extending around the burner chamber, and a lateral passage that connects with the lower end of the radiator element and with an exhaust flue.

2. A heater of the character described embodying an upright combustion chamber and a side radiator element communicating therewith at its top; characterized by a combined burner and passage member located at said lower end communication and embodying a body having therein a burner chamber, a vertical air passage extending around the burner chamber, and a lateral passage that connects with the lower end of the radiator element and with an exhaust flue; said burner chamber and said passages in the body forming an integral cast construction.

3. A heater of the character described embodying an upright combustion chamber

and a side radiator element communicating therewith at its top; characterized by a combined burner and passage member located at said lower end communication and embodying a body having integrally therein a burner chamber, a vertical air passage extending around the burner chamber and a passage having a leg that connects with the lower end of the radiator element at one side of the body and extends around to the back of the body and there connects with an exhaust flue, the outer wall of the air passage being also a wall of said last named passage.

4. A heater of the character described embodying an upright combustion chamber and a side radiator communicating therewith at its top; characterized by a combined burner and passage member located at said lower end communication and embodying a body having integrally therein a burner chamber, a vertical air passage extending around the burner chamber and a passage having a leg that connects with the lower end of the radiator element at one side of the body and extends around to the back of the body and there connects with an exhaust flue, the outer wall of the air passage being also a wall of said last named passage; there being an opening in said air passage wall, and a gas supply pipe for the burner extending through the said leg of said last mentioned passage and through said opening to the burner.

In witness that I claim the foregoing I have hereunto subscribed my name this 21st day of July 1920.

AUGUST J. HARTFIELD.
